UNITED STATES PATENT OFFICE.

THOMAS F. DOWNEY, OF CHICAGO, ILLINOIS.

STEAM-BOILER.

1,097,402.

Specification of Letters Patent.

Patented May 19, 1914.

Application filed May 1, 1909. Serial No. 493,251.

To all whom it may concern:

Be it known that I, THOMAS F. DOWNEY, a citizen of the United States, residing at Chicago, in the county of Cook and State 5 of Illinois, have invented certain new and useful Improvements in Steam-Boilers, of which the following is a specification.

One of the objects of this invention is to produce an internally-fired fire-box boiler.

10 Another object of the invention is to produce an improved heater especially adapted for warming buildings and comprising, in a unitary structure, a boiler, a furnace and an ash receptacle.

15 Another object is to provide a flue for boilers of the Scotch type, in which the pressure upon the flue is borne by the tensile strength of the flue plates.

Another object is to provide such a construction of return-tubular boilers that there shall be ample fire-box space and so 20 that soot and dust carried by the gases may have an opportunity to settle before the gases enter the return flues.

25 Another object is to provide improved means for bracing fire-box boilers.

A further object is to provide a special garbage-burning grate in a steam-generating unit.

30 A further object is to construct a boiler in such a way that the crown sheet shall be covered with water even though the general water level has been reduced below the top of the fire-box, thereby avoiding overheating 35 the crown sheet.

A further object is to avoid the formation of seams or rivet heads within the fire-box.

40 A further object is to obviate the necessity for using stay bolts in fire-box boilers.

The invention also relates to the other improvements in boilers and furnaces hereinafter set forth.

45 In the accompanying drawings, Figure 1 is a longitudinal vertical central section through a steam-generating unit embodying the features of my invention. Fig. 2 is a transverse section on line 2 2 of Fig. 1. Fig. 3 is a diagrammatic cross-section of a Scotch 50 or marine boiler embodying my invention.

The embodiment shown in Figs. 1 and 2 is especially adapted for steam-heating purposes. It comprises a shell 1 of generally circular form in cross-section, the lower portion 55 of said shell having an opening there-

in extending from one end of the boiler to the other. This opening, in the present instance, is of sufficient width to accommodate the grate. At opposite sides of the opening the shell 1 is continued in the two 60 vertical portions 2 which constitute supports for the boiler and side walls for the ash-pit. Bars 2^a of channel or other suitable cross-sectional form may be secured to the lower edges of the portions 2. The front 65 tube sheet 3 and the rear tube sheet 4 are of substantially similar outline and have outturned flanges 5 by means of which they are secured to the shell 1. The combustion chamber extends longitudinally of the shell 70 1 from one end thereof to the other. It is formed by a crown sheet 6, and two side plates 7, said plates being curved on the arcs of circles of the same radius as is the shell 1. The lower edges of the side plates 7 75 are riveted or otherwise secured to the shell 1 and preferably to the vertical portions 2 below the grates, as at 8. The upper edges of the side plates 7 and the side edges of the crown sheet 6 are secured together and 80 stayed by two plates 9, the edges of plates 6 and 7 lying at opposite sides of the plates 9 and being connected thereto, as by rivets 10. Rivets 11 connect the upper edge portions of the stay plates 9 with the shell 1. 85 The ends of the plates 6 and 7 are secured to the front and rear tube sheets by means of flanges 12 formed on said plates. As shown in Fig. 2, the plates 6 and 7 are arranged with their concave sides disposed 90 toward the space within which pressure exists in use, and consequently the steam pressure is resisted by the tensile strength of the plates 6, 7 and 9. The plates 9 serve as 95 calking strips between the edge portions of the plates 6 and 7. In the plates 9 are openings 13 to permit of a circulation of the water. The spaces between the shell 1 and the plates 6 and 7 contain a suitable number 100 of return flues 14.

The grate 15 may be of any suitable form.

16 represents a bridge wall which may be of any common or preferred form.

The combustion chamber 17 has a fire door 18. A smoke box or breeching 19 is formed 105 by an extension of the shell 1 beyond the front tube sheet, and the lower wall 20. Said smoke box is provided with a door 21.

22 is the smoke flue.

At the rear end of the boiler a chamber 23 110

is formed by an extension of the shell 1 and by a rear vertical wall 24. Said wall may have a lining 25 of brick or tile.

If desired, a grate may be provided in the rear portion of the flue formed by the plates 6 and 7, for the destruction of garbage. As herein shown, an upwardly and rearwardly inclined grate 26 extends from a low wall 27 to the wall 24, garbage being introduced through an opening 28 which is normally closed by a door 29. Preferably an opening 30 is provided in the lower portion of the grate 26 through which the ashes may pass into the ash pit 31. Said opening is normally closed by a slide 32 which may be operated by a rod 33. Below the grate 15 is an ash pit 34. Cleaning openings 35 afford access to the ash pits 31 and 34.

The inner ends of the grates 15 and 26 may be supported in any suitable manner other than that herein shown.

In operation, gaseous products of combustion pass from the chamber 17 to the chamber 23 and thence through the flues 14 to the smoke box 19. In traveling from the chamber 17 to the chamber 23, a large portion of the soot and dust carried by the gases settles upon the floor upon which the boiler is set, thereby avoiding the rapid formation of dust deposits in the flues 14. It will readily be understood that the dust may be removed from the floor much more easily than from the flues.

The plates 9 effectively stay the shell 1 and the plates 6 and 7.

The flue or fire-box formed by the plates 6 and 7 is very strong and is of ample size to accommodate the grate or grates.

It will be observed that the crown sheet 6 is so shaped that it will remain covered with water as long as possible during a lowering of the water level, thereby greatly lessening the danger of overheating said sheet.

A boiler and furnace constructed as shown in Figs. 1 and 2 is a unitary structure which may be set directly upon a floor and which requires no inclosing or supporting brick-work.

An internal flue may be formed in a boiler

of the Scotch or marine type by means of plates 36 37 38 39 as shown in Fig. 3, said plates being curved on the same radius as the shell 1^a and being stayed by means of plates 40 41. The latter have openings therein to permit of a circulation of the water. The grate may be supported within the flue in any preferred manner.

I would have it understood that the invention is not limited to the proportions and details herein illustrated and described, for various modifications will occur to persons skilled in the art.

I claim as my invention:

1. In a steam boiler, a generally circular shell having an opening from end to end thereof along its lower side and having parallel vertical supporting portions projecting at each side of the opening; a longitudinally disposed combustion chamber inclosed in the shell and comprising a top wall and two side walls, each of said walls being composed of a single transversely continuous and concavo-convex plate and presenting its convex side to the interior of the combustion chamber, the side plates having their lower edge portions jointed to the shell at opposite sides of the opening, and stay plates jointed to the shell and also to the upper edge portions of the side plates and to the side edge portions of the upper plate, no portion of said combustion chamber projecting above a horizontal plane passing through the axis of said boiler.

2. In a steam boiler, a generally circular shell having a separate longitudinally disposed combustion chamber inclosed therein, the combustion chamber comprising a top wall and two side walls, each of said walls being composed of a single transversely continuous concavo-convex plate, and presenting its convex side to the interior of the combustion chamber, and a pair of stay plates joined to the shell and also to mutually adjacent edge portions of said wall plates.

THOMAS F. DOWNEY.
